ELECTRIC COUPLING SYSTEM

Application filed January 9, 1924, Serial No. 685,148, and in Mexico January 22, 1925.

This invention relates to electric coupling systems, more particularly for the amplification of electrical impulses having a relatively high frequency.

5 In the amplification of electrical impulses it has been found difficult to obtain satisfactory amplification because of capacitative effects between elements of the apparatus employed. Such capacitative effects make possible undesired local oscillations, the tendency to the generation of which materially reacts upon the degree of effectiveness of the amplifier.

10 It is an object of the present invention to make available for subsequent use over a relatively wide range of frequencies the energy caused to flow in the output circuit of an amplifier at the same time governing the tendency to make the amplifier act in itself 15 as a generator of local oscillations.

20 The invention has perhaps its widest field of utility in connection with an amplifier of the vacuum tube type as a means of coupling between adjacent vacuum tubes arranged in 25 so called cascade relationship, or as a means of coupling between any types of apparatus depending for their operation on a supply of 30 electrical impulses wherever the tendency to generate local oscillations as a result of 35 capacitative feedback on the part of any portion of the apparatus is detrimental to the operation of the system. It may, however, be employed in connection with amplifiers of any desired type having the capacitative characteristics above referred to.

Other objects and features of the invention will appear from the following description taken in connection with the appended claims.

40 "Vacuum tube" as used in this application refers to any thermionic device comprising an input electrode referred to as the "grid", an output electrode, referred to as the "plate" and a common electrode, referred 45 to as the "filament"; the electric power output being controlled by the input voltage between the grid and the filament.

50 "Electric coupling system" as used in this application refers to any electric circuit arrangement interposed between a vacuum tube

and some succeeding device which circuit is arranged to utilize power released by the vacuum tube for the building up of a resonant voltage for impression on the input terminals of the succeeding device.

55 By "input impedance" as referred to in this application is meant the impedance of the electric coupling system or circuit arrangement between the filament system and the connection to the plate of the vacuum 60 tube.

65 "Filament system" as used in this application includes all points connected with the filament proper which have substantially no high frequency alternating voltage between 70 themselves and the filament.

70 It is assumed throughout that suitable means for actuating the vacuum tube by the impression of a voltage between its input terminals are provided.

75 By properly selecting the electrical characteristics of an inductive reactance inserted in the plate circuit of a vacuum tube, the variations in voltage between the elements within the tube may readily be made such that energy will be fed back from the plate to the grid circuits through the plate-grid capacity of the tube. Such feedback will tend to cause the tube to act as a generator of local oscillations which will interfere with the proper operation of the vacuum tube as an amplifier. To prevent such oscillations, it has been customary to introduce opposing reactions, such as sources of loss or couplings between the plate and grid circuits which will 80 oppose that of the plate-grid capacity. Sources of loss have the disadvantage of lowering the selectivity in a tuned amplifier; and opposing couplings introduce complications of construction and adjustment that 85 may increase the cost. In accordance with this invention the effectiveness of the capacitative feedback is so reduced by limiting the alternating component of voltage between the plate and the filament that oscillations are prevented without introducing any 90 opposing reactions; or, in other words, the operation of the amplifier is made stable, essentially by employing a sufficiently low input impedance in the coupling system. At 95

100

the same time, a satisfactory degree of amplification, together with high selectivity, is secured by building up between the output terminals of the coupling system a resonant voltage many times higher than the filament-plate voltage.

A feature of this invention is the provision of means for maintaining the conditions just stated over a relatively wide range in frequency, by suitably varying the ratio of the resonant output voltage to the filament-plate voltage.

Referring to the drawings:—

Fig. 1 shows diagrammatically one form 15 of the invention embodied in a stage of a tuned radio-frequency amplifier, in which the amplitude of filament-plate voltage variation is limited.

Fig. 2 shows diagrammatically a modified 20 form of the invention including an insulating transformer in the electric coupling system.

Referring to Fig. 1, there is provided a 25 three-electrode vacuum tube 10 of the amplifying type, which may comprise an evacuated chamber 11 formed of glass or the like. The vacuum tube 10 includes a heated filament 12 for emitting electrons, a plate 13 upon which the electrons impinge and a grid 14 for controlling the passage of electrons. For heating the filament 12, a source of energy, such as a battery 15, is provided, the filament current being controlled by means of a usual filament rheostat 16.

35 For maintaining the plate 13 at a high positive potential relative to the filament 12, there is provided a source of electric potential, such as a battery 20, having its negative terminal connected to one terminal of the 40 filament. Included in the circuit of the battery 20 is a choke coil 21 preferably so constructed as to have a minimum capacity between its windings. There is also provided a pair of condensers 22, 23 and an inductance 45 24 connected in series with a conductor 25 and a conductor 26, collectively forming a closed oscillatory circuit 22, 25, 23, 24, 26, 20, which may be tuned to resonance with any desired 50 preselected frequency. In case it is not desired to include the plate battery 20 in the oscillatory circuit, it may be connected immediately adjacent the filament battery 15, as is the more common practice. The position 55 of the plate battery has no particular relation to this invention. The terminals of the inductance 24 are connected to binding posts 27, 28 respectively, which form the output terminals of the amplifier stage and which may be connected to a subsequent 60 stage, to a detector or to any other desired device. The capacities of condensers 22 and 23 are so arranged as to be varied simultaneously, as for example by means of a single manual device, such as a knob, whereby the 65 frequency adjustment of the system is made.

The ratio of capacities of condensers 22 and 70 23 for effective operation at each setting, is determined by the constants of the vacuum tube 11 and of the coil 24. For the amplification of electrical impulses having frequencies ranging from 500,000 to 1,500,000 cycles per second, the capacity of the condenser 22 may be, for example, eight to fifteen times that of condenser 23, when using a coil 75 of ordinary size and an ordinary radio receiving vacuum tube having a mutual conductance of 0.3 to 0.4 millimho; with vacuum tubes of higher mutual conductance, the ratio of capacities should be correspondingly higher. The ratio of capacities of the condensers may be preselected for any desired 80 range of adjustment.

The grid 14 of the tube 10 is connected to an input terminal 30 by means of a conductor 31 and one of the terminals of the filament 12 is connected to an input terminal 32 by means of a conductor 33. Thus when a voltage is applied across the terminals 30, 32, there is produced a voltage between the grid 14 and the terminal of the filament 12. The action of the vacuum tube in a well known manner, as a result of this voltage, produces a change in the plate current flowing between the plate 13 and the filament 12 and thus a change in the current in the external plate circuit. The choke coil 21 effectively resists changes in current passing therethrough. Accordingly, a change in the plate current must produce a change in the electrostatic charge of the condenser 22, and this condenser gives out or receives energy in proportion to the change in plate-filament conductance. Hence the condenser 22 if relatively large, governs the variations in filament-plate voltage. The change of voltage 90 across the terminals of the condenser 22 upsets the equilibrium existing in the resonant circuit 22, 25, 23, 24, 26, 20 wherein the alternating voltage across the joint capacity 22, 23 is equal and opposite to that across the inductance 24. It follows that the voltage across 95 23, 24 changes in accordance with the voltage across the condenser 22 and that the voltage across the condenser 23 will be relatively greater than that across the condenser 22, in the inverse ratio of the capacities of 100 said condensers. The voltage across the inductance 24 will always readjust itself to 105 equal the sum of voltage across the condensers 22, 23. 110

Thus it will be seen that the condenser 22 acts to limit the amplitude of variation of filament-plate voltage and forms a part of a resonant circuit in which a relatively high 115 resonant voltage is built up.

Referring now to Fig. 2, there is provided a vacuum tube 10 and associated therewith a filament heating battery 15 and a plate potential battery 20, as in Fig. 1. In this modi- 120

fied form of the invention which materially differs from the form of Fig. 1 only in that the main resonant circuit is insulated from the input portion of the system, there is provided a condenser 301, and a coupling transformer 302 including a primary winding 303 and a secondary winding 304. One terminal of the primary winding 303 is connected to the plate of the tube 10 by means of a conductor 305. The other terminal of the primary winding 303 is connected in series with a choke coil 306 to the positive terminal of the battery 20.

For by-passing variations in plate current there is provided in shunt collectively with the battery 20 and the choke coil 306, a condenser 310. In shunt with the secondary winding 304 of the transformer 302 is a variable condenser 311 which in combination with the winding 304 forms a closed oscillatory circuit 312 which may be tuned to the frequency of the actuating impulses. The circuit 312 is connected to the terminals 313, 314 by means of conductors 315, 316 respectively. The condenser 301 of Fig. 2 corresponds to condenser 22 of Fig. 1, and the coil 306 corresponds to coil 21 of Fig. 1. The capacities of the condensers 301 and 310 are preferably selected so that the capacity of the condenser 301 is much greater than that of the condenser 310 and so that their joint capacity in shunt with the coil 303 will not cause the circuit including capacities 301, 310 and the coil 303 to be resonant to any frequency at which the device is to be operated.

With this arrangement it is advantageous to arrange condensers 310 and 301 so that the ratio of the magnitudes of their capacities can be altered at will, in order to obtain the best operating condition at any frequency to which the system may be tuned. Since the magnitudes of the capacities 310, 301 and 311 are interdependent for best effectiveness and since the combination of condensers 310 and 301 in connection with the inductance of coil 303 is preferably so chosen as not to greatly alter the tuning of circuit 312, either of condensers 310 and 301 may be made of fixed capacity, and the desired change in ratio of their capacities secured by making the other of the two of variable capacity.

In operation, the condenser 301 may be assumed to determine the amplitude of filament-plate voltage variation. At the same time condenser 301 determines the voltages set up in coil 303 and condenser 310 as a result of energy flow to maintain proper voltage distribution in circuit 301, 303, 310. Such flow of current through coil 303 will produce variations in flux associated with coil 303, causing the building up of a resonant voltage in the coupled oscillatory circuit 312. This resonant voltage may be made considerably the largest of any generated in the output circuit, and may be arranged for subse-

quent use by connections to output terminals as shown.

It will be seen that by application of the principle of governing the variations in filament-plate potential difference, I have made it possible to amplify impulses of high frequencies without objectionable inter-element capacitative transfer of energy from the plate to the grid circuits of the vacuum tube, thus mitigating the undesirable tendency of the vacuum tube to act in itself as a generator of local oscillations. The amplifier may, therefore, be operated with a high degree of effectiveness.

Although certain specific embodiments of the invention have been particularly shown and described, it will be understood that the invention is capable of modification and that changes in the construction and in the arrangement of the various cooperating parts may be made without departing from the spirit or scope of the invention, as expressed in the following claims.

What I claim is:

1. In a vacuum tube coupling system, the combination of a condenser connected directly from the plate to the filament system of a vacuum tube whereby the amplitude of the alternating voltage between the plate and the filament system is limited, independent means for completing a path for the direct plate current of said tube, a second condenser having one of its terminals connected to one of the terminals of the plate-filament condenser, a winding connected to the other terminal of the second condenser and to the side of the plate-filament condenser which is not connected to said second condenser, said winding forming with said condensers a closed resonant circuit in which the condensers are in series, and means for rendering a resonant voltage obtained from said winding available for subsequent use.

2. In a vacuum tube coupling system, the combination of a condenser connected directly from the plate to the filament system of a vacuum tube whereby the amplitude of the alternating voltage between the plate and the filament system is limited, independent means for completing a path for the direct plate current of said tube, a second condenser having one of its terminals connected to one of the terminals of the plate-filament condenser, a winding connected to the other terminal of the second condenser and to the side of the plate-filament condenser which is not connected to said second condenser, said winding forming with said condensers an adjustable closed resonant circuit in which said condensers are in series, said resonant circuit comprising three units, at least one of which units is adjustable, and means for rendering a resonant voltage obtained from said winding available for subsequent use.

3. In a radio-receiving amplifier stage the

- combination of a vacuum tube having a filament, a grid and a plate, an electric coupling system including self-inductance and capacity, output terminals in said coupling system between which a resonant voltage is built up, connections from said filament and said plate to said coupling system, said coupling system including adjustable tuning means and capacitative means simultaneously adjustable with said tuning means for maintaining at all frequencies the ratio of said resonant voltage to the voltage between said filament and said plate at such value as to maintain highly effective amplification and stable operation of said stage.
4. In a radio-receiving amplifier stage the combination of a vacuum tube having a filament, a grid and a plate, an electric coupling system including self-inductance and capacity, output terminals in said coupling system between which a resonant voltage is built up, connections from said filament and said plate to said coupling system, and a single manually controlled means for simultaneously adjusting a plurality of electrical elements to tune said coupling system and to maintain throughout the tuning range such ratio of said resonant voltage to the voltage between said filament and said plate as to maintain highly effective amplification and stable operation of said stage.
5. A radio-frequency amplification system associated with the plate circuit of a vacuum tube having a filament, a grid and a plate, said system including a condenser connected between the plate and the filament of said tube, and a second condenser and an inductance coil effectively connected in series with each other and between said plate and said filament, said second condenser having a smaller capacity, whereby the alternating voltage between said plate and said filament is much less than that across said coil and is insufficient to cause local oscillations.
6. A radio-frequency amplification system associated with the plate circuit of a vacuum tube having a filament, a grid and a plate, said system including a condenser connected between the plate and the filament of said tube, and a second condenser and an inductance coil effectively connected in series with each other and between said plate and said filament, said second condenser having a smaller capacity, whereby the alternating voltage between said plate and said filament is much less than that across said coil and is insufficient to cause local oscillations, said two condensers being controlled simultaneously by a single manual means, whereby the ratio of their capacities is maintained at a desired value while the resonant frequency of the circuit in which said condensers are connected is varied over the required frequency range.
7. A radio-frequency amplification system

associated with the plate circuit of a vacuum tube having a filament, a grid and a plate, said system including a condenser connected between the plate and the filament of said tube, and a second condenser and an inductance coil effectively connected in series with each other and between said plate and said filament, said second condenser having a smaller capacity, whereby the alternating voltage between said plate and said filament is much less than that across said coil and is insufficient to cause local oscillations, said two condensers being adjustable simultaneously by a single manual control, whereby the ratio of their capacities is maintained at a desired value while the resonant frequency of the circuit in which said condensers are connected is varied throughout a required frequency band by said manual control.

8. In a radio receiving amplifier stage, the combination of a vacuum tube having a filament, a grid, and a plate, an electric coupling system including self-inductance and a plurality of capacities forming at least one closed oscillatory circuit, output terminals in said coupling system between which a resonant voltage is built up, connections from said filament and said plate to points in said oscillatory circuit between which the alternating voltage accompanying said resonant voltage is maintained so low by means of a ratio between the values of said capacities that highly selective amplification and stable operation are secured.

9. In a radio receiving amplifier stage, the combination of a vacuum tube having a filament, a grid and a plate, an electric coupling system including at least one closed oscillatory circuit having therein self-inductance and a plurality of capacities, output terminals in said coupling system between which a resonant voltage is built up, connections from said filament and said plate to points in said oscillatory circuit between which the alternating voltage accompanying said resonant voltage is maintained so low by means of a ratio between the values of said capacities that highly selective amplification and stable operation are secured.

In witness whereof, I have hereunto set my hand this 4th day of January, 1924.

CARL E. TRUBE.
